The ornamental design for a chair, as shown and described.

DESCRIPTION

FIG. 1 is a perspective view of a first embodiment of the chair embodying the new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a perspective view of a second embodiment of the chair embodying the new design;

FIG. 9 is a front view thereof;

FIG. 10 is a rear view thereof;

FIG. 11 is a right side view thereof;

FIG. 12 is a left side view thereof;

FIG. 13 is a top view thereof; and,

FIG. 14 is a bottom view thereof.

FIGS. 1-14 show portions of a chair frame in broken lines.

FIGS. 8-13 also show an upholstered pad in broken lines.

The portions shown in broken lines are for environmental purposes only and form no part of the claimed design.

Stipple shading is added to FIGS. 1 and 8 to convey surface contouring; the stipple shading is not to be understood as conveying a particular surface finish.
